UNITED STATES PATENT OFFICE.

GEORGE W. WHITWORTH, OF CEDAR FALLS, IOWA.

CONCRETE-MIXER.

1,082,000.

Specification of Letters Patent. Patented Dec. 23, 1913.

Application filed November 19, 1912. Serial No. 732,277.

To all whom it may concern:

Be it known that I, GEORGE W. WHITWORTH, a citizen of the United States of America, and a resident of Cedar Falls, 5 Blackhawk county, Iowa, have invented certain new and useful Improvements in Concrete-Mixers, of which the following is a specification.

My invention relates to improvements in 10 concrete mixers, and the object of my improvement is to provide a light, portable, simply-constructed mixing-machine for cement, concrete or the like, adapted to be knocked down for transportation, and 15 whose parts are so fitted together as to be both convenient in use, readily dumped, and of inexpensive construction. This object I have accomplished by the means which are hereinafter described and claimed, and 20 which are illustrated in the accompanying drawings, in which:

Figure 1 is a side elevation of my improved concrete mixer. Fig. 2 is a rear end elevation of my said mixer. Fig. 3 is an 25 upper plan view of the mixing-drum of my said machine, with the middle portion thereof and the ends of the spindles broken away. Fig. 4 is a vertical transverse section of the drum shown in Fig. 3, on the line *a—b*, 30 looking in the direction indicated by the arrow. Fig. 5 is a right-hand elevation of the rear drum-cap or end, showing its inner face. Fig. 6 is a perspective view of the 35 inner face of the forward drum-cap or end casting.

Similar numerals of reference denote corresponding parts throughout the several views.

The mixing-drum of my machine is composed of a U-shaped body 1, open at the 40 top, and whose end edges are fitted within the flanges of the drum-heads 2 and 3, being held in place therein by lugs 24 cast integrally on the inner faces of the heads. 45 The sides and bottom flanges of said heads have outwardly-projecting integral lugs 16, oppositely-located lugs on said heads being connected by means of the headed rods 17 and nuts 18. The said heads are preferably 50 made of cast-iron with outwardly-projecting axial spindles 7 and 9 respectively which are seated in one-piece bearings 8 and 10, the weight of the drum serving to keep them in place. The outer end of the spindle 55 7 is squared to take the sleeve of a crank-

arm 13 provided with a handle, the sleeve being secured by a set-screw 14. The bearing-blocks 8 and 10 are secured by bolts 15 to the top integral transverse portions of the A-frames 11, the lower ends of the latter 60 having longitudinal connecting bars or feet 21, which permit the machine to be slid from place to place. The legs of said frames are connected on the right by crossed bars 20 and on the left by means of a horizontal 65 bar 19. These A-frames permit barrows or other receptacles to be placed therebetween to receive the contents of said drum when dumped.

The drum has a slidable cover 26. The 70 upper edges of the drum-body 1 are flanged over inwardly and horizontally. Referring particularly to Figs. 3, 4 and 6, it will be seen that the drum flanges and end edges are seated inside the flanges of the drum-heads and held in place by the studs 24. On the inner face of the forward head 3 is an inwardly-projecting horizontal shelf 27 spaced away from the side flanges of the head and being located below the level of 80 the partial top flanges 25 of said head. The head is open above the shelf 27 and a slide-way thus provided for the slidable cover 26, the latter having its forward end bent downwardly outside of said forward head at 4. Upon the top of the cover are the pair of handles 5 and 6. Spaced-apart parallel longitudinal slats 23 are secured to the top of said cover 26 near its longitudinal edges by means of the rivets 24. 90 The outer edges of said slats are raised and spaced apart enough from the cover to take slidably therebetween the inwardly-flanged longitudinal upper edges of said drum-body 1. The cover thus is made slidable along 95 the drum-flanges and when in place is very tight, and the contents cannot leak out, but when mixed, the cover may be slid forward and the contents dumped by inverting the drum.

Having described my invention, what I claim as new, and desire to secure by Letters Patent, is:

1. In combination, a receptacle, comprising flanged heads, one of which has a slot 105 adapted to receive a slidable closure, a U-shaped hollow body seated within the flanges of said heads, a slidable closure for said body, movable through the slot in said head, and means for detachably securing 110

said heads to said body, comprising lugs extending outwardly from the edges of said heads to furnish oppositely-placed pairs, and connecting-bars secured detachably between and to the lugs of each pair.

2. In combination, a receptacle, comprising flanged heads, one of which has a slot adapted to receive a slidable closure therethrough, a U-shaped hollow body seated within the flanges of said heads, a slidable closure for said body movably seated in the slot in said head, and means for detachably securing said heads to said body, comprising lugs extending outwardly from the edges of said heads to furnish oppositely-placed pairs, and connecting-bars secured detachably between and to the lugs of each pair.

3. In combination, a receptacle, comprising flanged heads, a U-shaped hollow body seated within the flanges of said heads and having its longitudinal edges bent over inwardly and horizontally to form flanges, one of said heads having the medial part of its upper flange removed with an adjacent portion of the head, to provide a horizontal opening therein, a cover adapted to slidably close the receptacle and having longitudinal guides adapted to fit slidably over the body-flanges, and means for detachably securing the said heads and body together, comprising lugs extending outwardly from the edges of said heads to furnish oppositely-placed pairs, and connect-

ing-bars secured detachably between and to the lugs of each pair.

4. In combination, a receptacle, comprising flanged heads, a U-shaped hollow body seated within the flanges of said heads and having its longitudinal edges bent over inwardly and horizontally to form flanges, one of said heads having the medial part of its upper flange removed with an adjacent portion of the head, to provide a horizontal opening therein, said head having a projecting horizontal integral shelf on its inner face spaced away from side flanges to admit the body edge therebetween and having its upper face flush with the lower limit of said horizontal opening, a cover adapted to slidably close the body and having longitudinal guide-bars secured on its upper face near its longitudinal edges adapted to slidably move over the said body-flanges, said cover being located just below said body-flanges with said guides resting on the flanges and the cover slidable through the said head opening over said integral shelf, and means for detachably securing said heads and said body together.

Signed at Waterloo, Iowa, this 31st day of Oct., 1912.

GEORGE W. WHITWORTH.
